(74) *Attorney, Agent, or Firm*—Townsend and Townsend and Crew LLP

(21) Appl. No.: **29/305,057**

CLAIM

(22) Filed: **Mar. 13, 2008**

The ornamental design for a coin-shaped fan blade assembly, as shown and described.

(51) **LOC (9) Cl.** 23-04

DESCRIPTION

(52) **U.S. Cl.** **D23/379**

(58) **Field of Classification Search** D23/377,
D23/379, 385, 411, 413; 416/5

See application file for complete search history.

(56) **References Cited**

FIGS. 1 through 5 show, including a front view, rear view, radial side view, front perspective view, and rear perspective view of coin-shaped fan blade assembly detailing my new design according to an embodiment of the present invention.
